E. E. BLACKBURN.

STOVE DOOR,

APPLICATION FILED APR. 30, 1921.

1,428,579.

Patented Sept. 12, 1922.

UNITED STATES PATENT OFFICE.

EDWARD E. BLACKBURN, OF MARION, INDIANA, ASSIGNOR TO HOOSIER STOVE COMPANY, OF MARION, INDIANA, A CORPORATION OF INDIANA.

STOVE DOOR.

Application filed April 30, 1921. Serial No. 465,793.

To all whom it may concern:

Be it known that I, EDWARD E. BLACKBURN, a citizen of the United States, residing at Marion, in the county of Grant and 5 State of Indiana, have invented certain new and useful Improvements in Stove Doors, of which the following is a specification.

My invention relates to stove doors and one of the objects of the invention is to provide in a device of this character, a construction for mounting the high closet doors in a cooking range so that they will not show any nuts or bolts, lugs or catches when the doors are closed or when they are lowered to open 15 position.

A further object is to provide a concealed hinge construction applicable to the lower side of an oven door, which will securely hold the door in horizontal position when 20 open, which is strong and simply constructed, easily assembled and which is not liable to get out of order.

With these general objects in view, my invention consists in certain novel and peculiar features of construction and combination of parts as hereinafter described and particularly pointed out in the claims, reference being had to the accompanying drawing in which similar characters of reference 30 indicate similar parts.

Figure 1 is an elevation showing my invention as applied to the high closet of a cooking range;

Fig. 2 is a section on the line 2—2 of 35 Fig. 1;

Fig. 3 is a section on the line 3—3 of Fig. 1;

Fig. 4 is a section on the line 4—4 of Fig. 2;

Fig. 5 is a fragmentary perspective view 40 of the rear side of a door showing the hinge lug and;

Fig. 6 is a fragmentary perspective view 45 of the door frame.

Referring more particularly to the drawings, 1 is the high closet of a cooking range, comprising a door frame 2 secured to the oven frame by bolts passing through holes in suitably disposed lugs 3 and also through 50 holes 4 in the flanges 5, located on the inner side of the door frame and thus being effectually concealed from view in the finished article.

The door frame is shown herein as cast in

one solid piece to provide openings for two 55 doors 6 and 7, and comprises end uprights 8, a center upright 9, a horizontal top member 10 and a horizontal lower member 11. This lower member is provided along its outer upper edge with a curved groove 12, which co- 60 operates with the curved lower end 13 of the door, the latter being laterally extended to provide pintles 21 provided with lugs 14, which are adapted to contact with the inner side of the upright members of the door 65 frame and to act as limiting stops when the door is in open position. The groove as thus located provides a horizontal shelf portion 19 and a vertical ridge or abutment 18 which latter terminates short of the side members 70 to provide a space 20 for the lug 14, when the door is closed. Where the side and end members contact with the lug on the hinge, they may be provided with concavities to snugly fit the cam shaped lugs. 75

The door frame may be set at angle so that when in closed position it will rest against webs 15, thereby dispensing with the necessity of springs or catches for holding it in closed position.

The door is cast in one piece to provide an open frame work in which is secured a suitable panel 16, and for operating the door, a knob 17 is secured to the said frame work.

In placing a door in position in the frame, 85 it is merely necessary to pass it through the door opening at a suitable angle and drop the lower end into the groove 12, where it fits loosely. The lower end of the door will then be held against translational movement inwards, by the ridge or abutment 18 and outwards, by the vertical uprights of the door frame. The advantage of this construction is that when both opened and closed, there are no projecting lugs or slots to be seen and 90 which adds materially to the appearance of the finished article. The construction also permits the same door to be used in right and left hand positions.

From the above description it will be apparent that I have produced a device of the character described, which possesses all the features enumerated as desirable, and while I have illustrated and described the preferred form of the invention, it will be understood that I reserve the right to all changes properly falling within the scope 100 and spirit of the appended claims.

Therefore what I claim as new and desire to secure by Letters Patent is:

1. An oven having a door frame comprising a bottom member and an upright member, the said members being provided with a bearing, that portion in the upright member opening on the inner side of the frame, a door pivotally mounted in the said bearing and having a stop for cooperating with the inner side of the upright member for holding the door in open position.
2. An oven having a door frame, comprising a bottom member and upright members, the bottom member being provided with a bearing, the upright members being open on their inner sides, an abutment defining the inner side of the bearing, a portion of the upright members defining the outer side of the bearing, a door pivotally mounted in the bearing and engaging the abutment to limit

inward translational movement thereof and pintles carried by the door for engaging the upright members to limit outward translational movement thereof.

3. An article of manufacture, a metal door frame, comprising upright members open on their inner sides, a bottom member provided with a longitudinal hinge groove having a vertical abutment on the inner side which terminates short of the upright members.

4. An article of manufacture, a metal door frame comprising upright members and a bottom member, a longitudinal hinge groove defined on the front solely by a part of the upright members and on the rear by a part of the bottom member.

In testimony whereof I affix my signature.

EDWARD E. BLACKBURN.
